G. H. GREIMAN,

CLEANING DEVICE FOR EXCAVATORS.

FILED NOV. 14, 1921.

Inventor
George H. Griman
By his Attorney
Merchant Kilgar

UNITED STATES PATENT OFFICE.

GEORGE H. GREIMAN, OF GARNER, IOWA.

CLEANING DEVICE FOR EXCAVATORS.

Application filed November 14, 1921. Serial No. 514,946.

To all whom it may concern:

Be it known that I, GEORGE H. GREIMAN, a citizen of the United States, residing at Garner, in the county of Hancock and State 5 of Iowa, have invented certain new and useful Improvements in Cleaning Devices for Excavators; and I do hereby declare the following to be a full, clear, and exact description of the invention, such as will enable others skilled in the art to which it 10 appertains to make and use the same.

My present invention provides an improved cleaning device or scraper for excavators of the power-driven type wherein 15 excavating devices, variously designated as shovels, buckets or spades, are employed.

Cleaning devices for the above purpose have generally been spring-pressed or yieldingly mounted to prevent breakage of the 20 machine elements when large rocks or other hard materials are picked up. Most frequently, such cleaning devices or scrapers have been spring-pressed back to normal position by movement reverse from their 25 yielding or rock-clearing movement; but sometimes, the cleaning devices or scrapers have been held in position by shearing pins, which would give away before the machine elements would break. The first noted ar- 30 rangement was objectionable because the resisting force in the cleaning device, or rather, in its spring, would increase throughout its rock-clearing movements; and the second noted structure was objectionable be- 35 cause it required the cleaning device or scraper to be re-set by hand after each yielding action.

In accordance with my present invention, I provide a rotatable cleaning device or 40 scraper that exerts maximum resistance to movement when in its normal position, that is released by its initial movement from normal position, that thereafter moves freely to re-set position, and that will be automatically re-set by continuation of its rotation in the same direction in which it is 45 forced from normal position.

This improved cleaning device, as here illustrated, is especially designed and particularly adapted for use in connection with excavators or ditchers of the type disclosed and claimed in my prior Patent #1,287,675, of date December 17, 1918, entitled "Excavator," and in this form, involves additional 55 features of novelty; but, obviously, the in-

vention is capable of much more extended use.

In the accompanying drawings, which illustrate the invention, like characters indicate like parts throughout the several 60 views.

Referring to the drawings:

Fig. 1 is a fragmentary side elevation, with some parts sectioned and some parts broken away, showing the application of my 65 improved cleaning device to a ditcher or excavator of the character above indicated;

Fig. 2 is an enlarged fragmentary horizontal section taken approximately on the line 2—2 of Fig. 1, but with some parts 70 in full;

Fig. 3 is a fragmentary section taken approximately on the line 3—3 of Fig. 1;

Fig. 4 is a perspective showing the right-hand scraper-supporting bracket; and 75

Fig. 5 is a perspective showing the left-hand scraper or rotary element of the cleaning device.

Of the parts of the excavator, in so far as they are shown, the numeral 6 indicates a horizontal portion of the framework to which is journaled one of the transverse conveyor shafts 7, which, as shown, carries a polygonal sprocket wheel 8. The numeral 9 indicates a heavy sprocket chain of the link belt type that runs over the sprocket 8 and over co-operating and driving means, not shown. Certain of the links of the chain 9 carry outstanding arms 10, to the flanged outer ends of which excavating devices here- 90 in designated as spades 11 are rigidly secured. These spades are curved on such lines that they are approximately concentric to the axis of the shaft 7 while passing around the same. The spade-carrying arms 10, transversely of their plane of movement, are narrow, and within their plane of movement have sufficient extension to give desired strength. 95

In this preferred arrangement, the cleaning device comprises two scrapers obliquely set one on each side of the plane of movement of the arms 10. Each scraper has a plurality of blades or operative ends. In the preferred arrangement, each such scraper 105 comprises a double-ended arm 12 provided at opposite ends with V-pointed scraper blades 13 preferably slightly curved in the plane of the arm. At their central portions, the scraper arms 12 are provided with sleeve- 110

like hubs 14 journaled on bolts 15 that work freely through the oblique faces 16 of supporting brackets 17 that are bolted or otherwise rigidly secured to the frame 6. On 5 their oblique faces, the brackets 17 are formed with annular flanges 18 and with diametrically opposite stop lugs 19. On opposite sides of its hub 14, each scraper arm 12 is provided with stop lugs 20 that are 10 adapted to engage the stop lugs 19 of the brackets 17 and thereby stop the scraper in its operative position shown in Fig. 1. The lugs 19 and 20 are beveled preferably on both sides, for an important purpose which 15 will presently appear.

At its extended end, the pivot bolt 15 is provided with a nut 21 and co-operating washer 22. A coiled spring 23 is placed around the bolt 15 and is compressed between 20 the washer 22 and a washer 24 that is placed directly against the end of the hub 14 and is adapted to engage the adjacent face flange 16 of the co-operating bracket 17. A washer 25 is shown as placed between 25 the head of the bolt 15 and the adjacent face of the scraper arm 12.

Here it is important to note that the sleeve-like hubs 14 of the scraper arms 12 are of such length that when the scrapers 30 are in normal position or in any other position, except when the lugs 20 are being forced over the lugs 19, the springs 23 will press the washers 24 against the hubs 14 but will not frictionally press the arms 12 35 against the supporting brackets. Hence, the scrapers will freely move except when the stop lugs 19 and 20 are in contact.

The tension of the springs 23 will be so 40 adjusted that the beveled stop lugs 19 and 20 will hold the scrapers in operative positions, against all such forces as will be exerted in the normal scraping or cleaning action, such as required to dislodge from the excavator spades or blades all sticky earth, 45 and the like. If, however, a rock of considerable size should be carried against one or the other of the scrapers and should exert a force thereon somewhat closely approaching the breaking point, then the beveled engaging faces of the lugs 19 and 20 will cause 50 the scraper arms to move laterally against the tension of the springs 23, and thus the lugs 20 will be caused to ride over the lugs 19 and the engaged scraper arm will move 55 rotatively and permit the rock to pass. The rock, in passing, will turn the opposite end of the scraper arm into the path of movement of the load on the next excavating 60 spade so that the following load will complete the movement of the scraper into operative position where the lugs 19 and 20 again become engaged.

Obviously, with the bevel-ended scraper arm, the scrapers will be given half rotation for each tripping or releasing move-

ment. The scraper does not at any time make a return movement but always an advance movement or step by step rotation in the same direction, to wit: in the direction indicated by the arrow marked adjacent thereto in Fig. 1. With this arrangement, the force required to move a scraper from its normal position may be varied, at will, by adjustments of the tension of the springs 70 23. Also, the amount of bevel given to the 75 co-operative faces of the lugs 19 and 20 will influence the tripping action. Otherwise stated, the greater the bevel of said lugs, the greater must be the tension of the springs 23 to set the scrapers to trip under any desired force. 80

The scrapers or cleaning devices illustrated in the drawings are in a very novel relative arrangement for the particular application illustrated, and, in practice, has been found very highly efficient for such purpose. However, the invention is capable of many modifications to adapt them for other or different applications or uses. 85

The rotary scraper arms illustrated in the drawings are made in rights and lefts and the lugs 19 and 20 are beveled on both sides so that, by transferring or interchanging said rotary scraper arms, they may be used regardless of the direction in which the endless conveyor belt and its excavator spades or devices are arranged to travel. 90

What I claim is:

1. An excavator cleaning device comprising a rotary member having a plurality of 100 projecting scrapers, and a yielding stop adapted to be overcome by excessive pressure to permit said scraper-equipped member to rotate in a constant direction from one operative position to another. 105

2. The construction defined in claim 1 in which said scraper-equipped member is free for rotation except when stopped in an operative position.

3. The combination with an endless excavating belt, of a cleaning device therefor comprising a rotary member equipped with a plurality of scrapers, co-operating stops for stopping said rotary member with a scraper thereof in operative position, and a 110 spring tension device yieldingly holding said stops co-active but permitting said stops to pass under excessive pressure. 115

4. The construction defined in claim 3 in which said spring tension device is held out of action except when one of said stops is forced past the other. 120

5. An excavating belt in combination with a cleaning device comprising a bearing bracket, a bolt passed therethrough, a 125 scraper arm pivoted on said bolt and having a plurality of projecting scraper blades, said arm having a hub projecting slightly through said bracket, said arm and bracket having co-acting bevel stop lugs, and a 130

spring anchored to said bolt normally pressing against the hub of said arm and arranged to re-act upon said bracket when said stop lugs are being forced the one past

5 the other.

6. The construction defined in claim 5 in which said stop lugs are beveled on both sides thereby making the cleaning device reversible in respect to the operative direction of rotation.

10 7. The combination with an excavator belt provided with projecting arms, and excavating spades or blades carried by and project-

ing on both sides of the outer ends of said arms, of a cleaning device comprising two 15 rotary scraper arms obliquely set on opposite sides of said belt and each provided with a plurality of projecting scraper blades arranged to work in the angles between said arms and spades, said arms being rotatable 20 in a constant direction, and yielding stop devices for intercepting rotation of said arms and to stop the same with certain of the scrapers thereof in operative positions.

In testimony whereof I affix my signature. 25
GEORGE H. GREIMAN.
